DESIGN FOR A BEDSIDE SERVITOR

Mary E. Carr, Alice E. Camper, and Edwin
Luther Stevens, Bartlett, Ill.

Application July 27, 1939, Serial No. 86,278

Term of patent 7 years

To all whom it may concern:

Be it known that we, Mary E. Carr, Alice E. Camper, and Edwin L. Stevens, citizens of the United States, residing at Bartlett, in the county of Cook and State of Illinois, have invented a new, original, and ornamental Design for Bedside Servitors, of which the following is a specification, reference being had to the accompanying drawing, forming part thereof.

In the drawing:

We claim:

The ornamental design for a bedside servitor, as shown.
